UNITED STATES PATENT OFFICE

JOHN F. EYNCK, OF GUATEMALA CITY, GUATEMALA

CALENDAR ATTACHMENT

Application filed September 19, 1930. Serial No. 483,103.

This invention relates to an attachment for a calendar, the general object of the invention being to provide means whereby one can readily observe the current day on a calendar by simply glancing at the calendar.

This invention also consists in certain other features of construction and in the combination and arrangement of the several parts, to be hereinafter fully described, illustrated **20** in the accompanying drawings, and specifically pointed out in the appended claims.

In describing my invention in detail, reference will be had to the accompanying drawings, wherein like characters denote like or corresponding parts throughout the several views, and in which:

Figure 1 is a front view of the invention with a calendar thereon.

Figure 2 is a view with the calendar removed.

Figure 3 is a section on the line 3-3 of Figure 1.

Figure 4 is a perspective view of the horizontal member.

Figure 5 is a perspective view of the frame. Figure 6 is a perspective view of the rod.

Figure 6 is a perspective view of the rod on which the frame is slidably mounted.

Figure 7 is a perspective view of the vertical member.

In these views the numeral 1 indicates a

In these views the numeral 1 indicates a backing member which has its top edge turned over as shown at 2 so that the upper edge of a calendar pad 3 can be placed thereunder and fastened in position by the rivets 4 or the like which pass through the turned over part, the pad and the top part of the member 1. A vertical member 5 has a tongue 6 at its upper end which is passed through a slot 7 in the bight of the turned over part with portions of the bight resting against the top part of the member 5 so that said member 5 forms a support for the backing member when the tongue is placed on a wall fastener which is passed through the opening 8 in the top. One of the fasteners 4 may pass through the upper end member 5 as shown in Figure 2 and its lower end is also fastened in the backing as shown at 9. A

horizontal member 10 is slidably connected with the member 5 by the tongues 11 punched from the member 10 and bent over the edges of the member 5. Said member 5 is formed with a vertical row of spaced slots 12 any one of which is adapted to receive the bent part in a tongue 13 punched from the central part of the member 10. The slots 12 are so arranged that the movement of the member 10 from one slot to another will be equal to the distance between two horizontal rows of the numbers on the calendar.

As will be seen the members 5 and 10 are located under the calendar pad and a bar 14 passes over the front face of the pad and has its ends bent as shown at 15 to engage the spring tongues 16 punched from the ends of the member 10. Thus the bar is pivotally connected with the horizontal member 10 and by bending the ends of the bar to provide the parts 15' transverse movement of the bar is prevented. A rectangular frame 17 has its upper edge bent over as at 18 to form a space to receive the bar 14 so that the frame is suspended from the bar and can be swung on the bar. Tongues 19 are punched in the upper part of the frame and are bent over the bar to frictionally hold the frame in adjusted position on the bar. A bent tongue 20 is also punched in the top of the frame, this tongue being substantially V-shaped in cross section so that its apex will engage in any of a plurality of notches 21 formed in the bar 14 to properly position the frame on the bar with respect to the numbers indicating the days of the week. A cable or cord 22 is fastened to the lower edge of the central portion of the member 10 and extends downwardly through an opening 23 in the lower end of the vertical member 5 so that when this cord is pulled upon the member 10 with the bar 14 thereon will be lowered to cause its tongue 13 to engage the next slot 12 below the one previously engaged. A cord 24 is connected with the top of the member 10 and extends upwardly to a hole 25 in the backing member 1 through which the cord is passed, and thence the cord is passed through a second hole 26 in the backing member above the first hole and then the cord is passed through a 100

hole 27 in the top part of the member 5 from where the cord extends downwardly below the device.

Thus by pulling upon the cord 24 the member 14 is moved upwardly. The metal punched from the hole 27 is rolled as at 28 to prevent injury to the cord.

From the foregoing it will be seen that the horizontal member can be adjusted upwardly 10 or downwardly by the cords so as to place the bar 14 above that row of figures on the calendar with which the frame 17 is to be used. Then by sliding the frame on the bar the frame can be placed over that figure which is 15 the current day of the week. As will be seen from Figure 1 the framed figure will be observed instantly by one glancing at the calendar so that he will know that this figure is the current day of the week.

20 It is thought from the foregoing description that the advantages and novel features of the invention will be readily apparent.

It is to be understood that changes may be made in the construction and in the combination 25 and arrangement of the several parts, provided that such changes fall within the scope of the appended claims.

What I claim is:

1. A device of the class described comprising 30 a backing member having a vertical row of spaced slots, means for attaching a calendar sheet thereto, a horizontal member supported for sliding movement by the backing sheet and having a resilient tongue selectively 35 engageable in any one of the slots, a bar carried by the horizontal member and extending over the calendar sheet, and a frame slidably arranged on the bar and adapted to frame a figure on the calendar sheet.

40 2. A device of the class described comprising a backing member having a vertical row of spaced slots, means for attaching a calendar sheet thereto, a member slidably supported on the backing member under the 45 sheet and having a resilient tongue selectively engageable in any one of the slots, a vertically swinging bar carried by said slidable member and extending over the sheet, a frame slidably arranged on the bar and adapted 50 to enclose a figure on the calendar sheet, and means for adjusting the sliding member vertically without moving the sheet.

3. A device of the class described comprising 55 a backing member, means for connecting a calendar sheet thereto, a vertically arranged member connected with the backing member, a horizontal member slidably connected with the vertical member, the vertical member having spaced slots therein, and a horizontal 60 member having a tongue thereon for engaging any one of the slots, a bar carried by the horizontal member and extending over the calendar sheet, a frame slidably arranged on the bar, friction means for holding the frame 65 in adjusted position, means for facilitating

the adjustment of the frame over the desired figure on the calendar sheet, and flexible members connected with the horizontal member for raising and lowering the said member.

In testimony whereof I affix my signature. 70
JOHN F. EYNCK.
